BOAT HULL

Jack Davidson, 3316 E. Annadale, Fresno, Calif. 93725

Filed Feb. 11, 1971, Ser. No. 114,741

Term of patent 14 years

Int. Cl. D12—06

U.S. Cl. D71—1

FIG. 1.

FIG. 2.

FIG. 3.

FIG. 4.

FIG. 5.

FIG. 6.

FIG. 7.

FIG. 8.

FIG. 1 is a top plan view of the boat hull showing my new design.

FIG. 2 is a side elevation thereof with the opposite side being identical to the side shown.

FIG. 3 is a bottom plan view thereof.

FIG. 4 is a front elevation thereof.

FIG. 5 is a rear elevation thereof.

FIG. 6 is an outline view of the outer surface configuration of my boat hull, as taken along the line 6—6 of FIG. 1.

FIG. 7 is an outline view of my boat hull, taken on line 7—7 of FIG. 1.

FIG. 8 is an outline view of the configuration of my boat hull, taken on line 8—8 of FIG. 1.

I claim:

The ornamental design for a boat hull, as shown and described.
